UNITED STATES PATENT OFFICE

133,050

DESIGN FOR A TEXTILE FABRIC

John A. Houseman, Philadelphia, Pa., assignor to La France Industries, Philadelphia, Pa., a corporation of Pennsylvania

Application February 28, 1942, Serial No. 106,038

Term of patent 3½ years

To all whom it may concern:

Be it known that I, John A. Houseman, a citizen of the United States, residing at 5645 Miriam Road, city of Philadelphia, and State of Pennsylvania, have invented a new, original, and ornamental Design for Textile Fabrics, of which the following is a specification, reference being had to the accompanying drawing, forming part thereof.

The figure is a plan view of a piece of textile fabric showing my new design. The design unit is contained substantially between the dot and dash lines, which unit is repeated in regular succession as indicated by the extensions beyond the unit boundaries.

I claim:

The ornamental design for a textile fabric, as shown and described.

JOHN A. HOUSEMAN.
